UNITED STATES PATENT OFFICE.

WILLIS E. LA RUE, OF INDIANAPOLIS, INDIANA, ASSIGNOR OF ONE-HALF TO WILLIAM P. HALL, OF INDIANAPOLIS, INDIANA.

FAUCET.

1,336,970.

Specification of Letters Patent.

Patented Apr. 13, 1920.

Application filed February 16, 1918. Serial No. 217,498.

To all whom it may concern:

Be it known that I, WILLIS E. LA RUE, a citizen of the United States, and a resident of Indianapolis, county of Marion, and 5 State of Indiana, have invented a certain new and useful Faucet; and I do hereby declare that the following is a full, clear, and exact description thereof, reference being had to the accompanying drawings, in which 10 like letters refer to like parts.

This invention relates to new and useful improvements in faucet construction and is primarily adapted to be used in connection with soda fountains and the like for dispensing carbonated water, and the prime 15 feature of the invention is the provision of a non-leakable faucet.

A further feature of the invention is the provision of a faucet, no part of which will 20 require packing of any description to prevent leakage of the carbonated water therefrom.

A further feature of the invention is the provision of draining channels which prevent 25 the carbonated water from dripping or exuding from any part of the faucet, except at the drainage point. A further feature of the invention is in so placing the draining ducts that the drippings therefrom 30 will be excluded from sight, and a further feature of the invention is in so constructing the faucet that but a limited number of parts will be required in producing the faucet.

35 Further features of the invention will be hereinafter more fully set forth in the accompanying specifications.

In the accompanying drawings which are made a part of this application, Figure 1 is 40 a longitudinal sectional view through the faucet as seen on line 1-1 of Fig. 2, showing the same attached to a tank containing carbonated water. Fig. 2 is a sectional view as seen on line 2-2 of Fig. 1, showing the 45 valve or plug in closed position. Fig. 3 is a view similar to Fig. 2 with the valve or plug set to permit the carbonated water to freely flow through the faucet. Fig. 4 is a similar view of the valve or plug set to cause the 50 carbonated water to spray, or pass with force from the faucet. Fig. 5 is an elevation of the valve or plug removed from the faucet and Fig. 6 is a sectional view as seen on line 6-6 of Fig. 1.

55 Referring to the drawings in which similar reference numerals designate corre-

sponding parts throughout the several views; 1 indicates a faucet which is provided with a body portion 2, an extension 3 and a nozzle 4, which parts are formed integral.

The body 2 is provided with an opening 5 extending upwardly from the lower end thereof and tapered from the bottom to the top portion, said body portion having a neck 6 65 projecting upwardly therefrom and of less diameter than the diameter of the body and through the neck is formed a bore 7 for the reception of a shank 8 of a valve or plug 9, said plug being tapered to fit the taper of 70 the opening 5, and of less length than the length of the opening.

The lower end of the opening 5 is normally closed by a cap 10 which screws into the lower end of the opening 5 and in order 75 to hold the upper end of the valve or plug 9 firmly against the upper end 11 of the opening 5, any suitable form of spring mechanism 12 is attached to the lower end of the plug, the outer ends of the spring 80 mechanism pressing against the upper face of the cap 6 thus yieldingly holding the plug against the upper end of the opening at all times, and leaving a space at the lower end thereof to act as a drainage chamber. 85

Extending longitudinally and preferably through the upper portion of the extension 3, is a bore 13, to the inner end of which is attached a lead 14 from a tank 15, said tank being of the usual construction for containing 90 carbonated water. The bore 13 leads into the opening 5 and is adapted to register with the bifurcated ends 16 or 17 of a bore 18, which latter bore extends transversely through the plug 9. The nozzle 4 is provided with bores 19 and 20, with one or the other of which the bore 18 is adapted to register when the plug 9 is properly rotated, and in dispensing soda water or the like it is customary to first place the syrups 95 in the glass and substantially fill the glass with carbonated water after which the contents of the glass are thoroughly mixed by adding an additional supply of carbonated water under high pressure, this latter operation being accomplished by attaching the pipe 21 to the outer end of the bore 20, the pipe 21 being of a much less diameter than the bore 19. 100

The plug 9 is rotated through the medium of a handle 22 which has a square socket 23 to receive the square end 24 of the 110

shank 8, said handle having a sleeve 25 which fits around the neck 6 and the handle is held in position on the shank by introducing a screw 26 through the sleeve 25, the 5 inner end of the screw having a stud 27 which enters a slot 28 in the face of the neck 6, said stud also serving to limit the rotating movement of the handle and the plug.

The extension 3 is provided with an integral shoulder 29, which abuts against one face of the casing or fountain 30, while a nut 31 is threaded on to the free end of the extension 3 and against the opposite face of the case, said shoulder and nut holding 15 the faucet firmly in position. It has been the practice heretofore to provide various forms of washers and gaskets and the like to prevent leakage around the parts of the faucet, and it has always been found that 20 owing to the rapid disintegration of such washers it requires constant attention in renewing the washers and tightening the same before disintegration has destroyed them, and even with such constant attention the 25 faucets leak and such leakage is discharged upon the counter or else a vessel is provided to catch the same.

In applicant's device, however, these objectionable features are entirely overcome, 30 as there are no washers, gaskets or other sealing means used in any part of the faucet and in order to prevent drippings from discharging from the exposed portion of the faucet and thus descend upon the counter, 35 the plug 9 is provided with a peripheral channel 32 which extends entirely around the plug at a point adjacent its upper end and communicating with the peripheral channel is a pair of vertically-disposed channels 33 and 34.

The vertical channels 33 and 34 are so positioned that when the valve 9 is in closed position as shown in Fig. 2 of the drawings, 40 said channels will be positioned beyond the bores 19 and 20 respectively, so that should any of the carbonated water seep in between the valve 9 and the wall of the opening 5 it will be carried down through said channels and discharge at the lower end of the valve, 45 thus making it practically impossible for any of the water to pass into the bores 19 and 20, from whence it would drip upon the table or support below the faucet.

It will likewise be seen that the carbonated 50 water in passing upwardly around the valve 9 would encounter the channel 32, and as the water would naturally seek the course of least resistance it would pass around through said channel 32 and into the channels 33 and 34, whence it will be carried to 55 and discharged at the lower end of the valve 9.

In order to remove the drippings from 60 the lower end of the opening 5, the extension 3 is provided in its lower portion with

a bore 35, one end of which communicates with the interior of the opening 5 at a point below the lower end of the valve or plug 9, while the other end of the bore 65 communicates with the inner end of the extension 3, and as said end is within the fountain or case to which the faucet is attached, the drippings as they descend from the bore 35 into any suitable form of receptacle 36, 70 will be entirely excluded from view. It will 75 likewise be seen that in view of the limited number of parts required in producing the faucet it can be very cheaply constructed and will last indefinitely in view of the fact that there are no parts to wear or become 80 loosened after the device is once assembled and owing to the fact that there are no parts used which will become disintegrated from contact with the carbonated water, the faucet will require no attention 85 after once being properly attached to the soda fountain.

While this invention is shown and described as used in connection with a soda fountain and tank containing carbonated 90 water, it will be fully understood that the valve may be used for any desired purpose. It is not to be limited to use in connection with soda fountains.

The invention claimed is:

1. A faucet structure having an opening therein a plurality of longitudinally extending bores communicating with said opening, a valve adapted to fit in said opening, said valve having a peripheral channel adjacent 100 its upper end, a drainage chamber adjacent its lower end and vertically extending channels communicating with the peripheral channel and drainage chamber whereby the seepage from the parts of the faucet around 105 the valve will be gathered in said channels and conveyed to said chamber and discharged through one of said longitudinally extending bores.

2. A faucet structure having a hollow 110 body, a neck extending upwardly from the closed end of the body, said body having bores communicating therewith, a valve in said hollow body, a stem on said valve extending through said neck, means to engage and rotate said stem and valve, means to close the lower end of said body, and means to drain the interior of the body and prevent leakage through any of the exposed 115 portions of the faucet or stem, comprising a horizontal peripheral channel adjacent the upper end of the valve, vertical channels communicating with the horizontal channel, and a bore communicating with the lower portion of the hollow body for conveying 120 the liquid contents of the hollow body therefrom.

In witness whereof I have hereunto affixed my signature.

WILLIS E. LA RUE.
